CLAIM

The ornamental design for a flip-up light for a remote control, as shown and described.

DESCRIPTION

FIG. 1 is a right-side perspective view of a flip-up light for a remote control, showing my new design in a retracted position;

FIG. 2 is a left-side perspective view thereof;

FIG. 3 is an enlarged right-side elevational view thereof;

FIG. 4 is a left-side elevational view of FIG. 3;

FIG. 5 is a top plan view of FIG. 3;

FIG. 6 is a bottom plan view of FIG. 3;

FIG. 7 is a rear elevational view of FIG. 3;

FIG. 8 is a front elevational view of FIG. 3;

FIG. 9 is a right-side perspective view thereof, illustrated in an extended position; and

FIG. 10 is an enlarged left-side perspective view of FIG. 9.

FIG. 11 is an exploded right perspective view of FIG. 3, a logo and text omitted for clarity of design;

FIG. 12 is an exploded right-side elevational view of FIG. 3; and,

FIG. 13 is an exploded left-side perspective view of FIG. 3. The broken lines showing a remote control in FIGS. 1, 2 and 9 depict environmental matter and form no part of the claimed design. The remaining broken lines show portions of the flip-up light that form no part of the claimed design.
